UNITED STATES PATENT OFFICE.

WILLIAM P. BETTENDORF, OF DAVENPORT, IOWA.

BODY AND TRUCK BOLSTER FOR RAILWAY-CARS.

SPECIFICATION forming part of Letters Patent No. 679,494, dated July 30, 1901.

Application filed December 27, 1899. Serial No. 741,764. (No model.)

To all whom it may concern:

Be it known that I, WILLIAM P. BETTENDORF, a citizen of the United States, and a resident of Davenport, in the county of Scott and State of Iowa, have invented certain new and useful Improvements in Body and Truck Bolsters for Railway-Cars, of which the following is a full, clear, and exact description, reference being had to the accompanying drawings and to the letters and figures of reference marked thereon.

The object of my invention is to provide a body and a truck bolster for cars made from a novel form of rolled-steel beams, which is so constructed as to form a truss capable of withstanding the draft strain of the car, as well as supporting the maximum of weight and equally distribute the same, while at the same time making a very light bolster at a minimum of expense. This I accomplish by the mechanism hereinafter fully described, and particularly pointed out in the claims.

In the drawings, Figure 1 shows a side elevation of about two-thirds the length of the body and truck bolster in their relative positions, showing the portion of the half, the end of which is broken away, in longitudinal vertical section. Fig. 2 is a transverse vertical section taken on dotted line 2 2, Fig. 1. Fig. 3 is a plan view of my improved body-bolster inverted. Fig. 4 is a plan view of my improved truck-bolster. Fig. 5 is an end view of said bolster in the relative position shown in Fig. 1. Fig. 6 is a transverse view of a cut-off end of the body-bolster. Fig. 7 is a perspective view of a broken-away end of the truck-bolster. Fig. 8 is a transverse section of the body-bolster, taken on line 8 8 of Fig. 5. Fig. 9 is a perspective view of a rolled-steel beam such as is employed in the construction of my improved bolster.

My improvements are applicable to both the body and truck bolsters of a railway-car, and in each of these forms of bolster the principal feature consists of a single truss so constructed as to possess all the elements of load-sustaining qualities of that class of bolsters using two parallel beams suitably tied together and to possess in addition thereto a transverse strength greatly exceeding that heretofore possessed by said bolsters.

In making my bolsters I employ an upper

and a lower section of a peculiarly-constructed rolled-steel beam, so arranged that their sides are bounded by the same vertical planes. 55 This rolled-steel beam consists of a flat plate *a* of suitable width and thickness, which are the same throughout the entire length of the beam. Between each longitudinal side of this beam and the center of width thereof it 60 has projecting at right angles from one of its broad surfaces two corresponding parallel webs *b*, and it is provided with longitudinal beads *c*, preferably on the same side as that from which said webs project, the outer contours of which are preferably next and flush with the longitudinal sides of the beam. 65

The upper section *A* of the rolled - steel beam *a b c*, used in making the body-bolster, is straight its entire length and is placed so 70 that its webs project downward, whereas the lower section *B* of said rolled - steel beam, which is placed so that its webs project upward, has its central portion arranged parallel to said upper section *A* and its end portions 75 on either side of said central portion bent toward said upper section, so that the edges of its longitudinal webs *b* come in contact with the edges of the webs *b* of said upper section at a point about ten or twelve inches from 80 the ends of the bolster, from which point the end portions of said lower section are so bent that said end portions are parallel to section *A* and have their meeting edges in contact therewith, as shown. 85

The parallel central portions of the upper and lower sections *A* and *B* are connected by rectangular vertical plates *C C*, which are secured, preferably, to the inner vertical surfaces of the webs *b b* thereof, coming in the 90 same vertical plane, by transverse bolts *D*. These plates *C* may be perfectly flat their entire length and breadth; but I prefer to make them of short sections of rolled-steel beams, having their side edges correspondingly bent at right angles thereto to form flanges *d d*. Plates *C* are also provided with longitudinal parallel ridges *e e*, the sides of which next the flanges *d* are at right angles to the broad sides of said plate, and each 100 ridge is so located that when the plate is secured to the webs *b* of the sections *A* and *B* the edges of said webs bear against the flat sides of said ridges and the flanges *d d* will

bear against the adjacent portion of the broad sides of the said sections A and B. Plates C are secured to the webs of the upper and lower sections by transverse bolts D, as 5 stated. I prefer to use four of these bolts D for securing both the upper and lower side portions of these plates C to sections A and B and to place them at equal intervals apart in the same horizontal plane. The end bolts of 10 the series have the portions thereof coming between the plates C pass through spacing-sleeves f, the length of which are such that when the bolt-heads are swaged the plates C are securely clamped between the heads of 15 the bolts D and the ends of the spacing-sleeves. These sleeves may be of the same diameter throughout their length; but I prefer to provide their ends with flanges f', one side edge of which is elongated in suitable manner and 20 has its outer end cut off straight at right angles to the major axis of the same, so that when in use such straight edge will bear against the flanges of the plate C, as shown. The two intermediate bolts D of each series 25 extend through sleeves g, which latter are the same in every substantial respect as sleeves f, excepting that they are connected at about their centers of length by a cross-bar g', through which the vertical guide-opening for 30 the king-bolt is made. Plates C and the individual and siamese sleeves f and g, when united by the bolts D to the upper and lower section A and B, make a very strong central filler for the bolster, which latter when connected to the sill-timbers and other parts of 35 the car is amply able to withstand the draft strain of the car, which is transverse thereto. The central portion of the bolster is further reinforced to withstand this draft strain by 40 the plate of the male bearing E, secured to the under surface of the lower section B by rivets 22, passing down through the same near each side and through plate d thereof between its longitudinal sides and the webs b of the same. 45 The ends of the sections of beam A and B, composing the body-bolster, are secured together on each side by vertical bolts F F, which pass vertically down through the marginal portions of plates a thereof between the 50 webs b and the heads of said sections, and by vertical bolts G G, passed vertically down through plates a of said upper and lower sections at a point near the end of the bolster and just inside of the webs b of the same. 55 These vertical bolts F and G may be passed through the two sections at any other point near the ends of the bolster, if desired; but I prefer them to be placed as indicated, because they thus afford greater strength and 60 rigidity to the bolster and at the same time can be utilized to assist in holding the end plate K in place, as will hereinafter be more fully explained.

I could confine myself to the use of the 65 bolts F and G alone to secure the ends of the upper and lower sections of the bolster together. I prefer, however, to use a suitable

casting in conjunction with these bolts, which will not only reinforce the bolts a of these sections at the point where said bolts pass therethrough, but will also clamp the same, so as to resist both the transverse displacement and longitudinal strain of said sections. This casting consists of a key h, the contours of which are preferably rectangular and is of 75 such length that it can just pass through corresponding rectangular recesses in the adjacent meeting edges of the webs of the sections. This key connects two substantially corresponding rectangular plates i and j, one of 80 which is adapted to bear against the outer vertical surface of said webs and the other of which is adapted to bear against the inner vertical surface of the webs next the recess in which said key is seated. These plates i and j 85 are of substantially corresponding dimensions, and the outer one extends horizontally toward the center of the bolster a short distance, and has made integrant therewith and arranged at right angles thereto a vertical 90 sleeve, which is so located that the bolts F can pass therethrough, and is of such vertical dimensions as to reinforce the plate a where said bolts pass through the same. The plates j, made integrant with the inner end of said 95 key, extends horizontally in the opposite direction to plate i to a point near the ends of said sections, where it merges into an upper and a lower knuckle m m, which are so located that the bolts G can pass down therethrough, and which are of such dimensions and are so located that they reinforce the plate a of said sections, which said bolts G pass therethrough.

I represents an end plate, the contours described by the edges of which are such as to follow the contours of the ends of the upper and lower sections of the bolster when the same are secured together. This end plate is secured to the end of the bolster by means 110 of lugs o o, projecting inwardly therefrom at a point about the middle of its height and so that the ends of the same will enter between the knuckles m m of the plate j, so that the bolts G, when extended down through the 115 plates a of the upper and lower section and said knuckles can pass through vertical openings in the same and thereby hold said end plate in place. This end plate is made to assist in the holding of the upper and lower 120 sections together by having its edges provided with inwardly-projecting flanges which lap over and bear against the sides of the ends of said sections, substantially as shown.

The truck-bolster also consists of an upper 125 section R and lower section S of the rolled-steel beam a b c, the central portions of which are connected by vertical plates o similar in every substantial respect to plate C, hereinbefore described, except that it is slightly 130 wider, so as to hold the central portions a little farther apart than as shown in the body-bolster. In the truck-bolster the end portions of each the upper and lower sections

thereof are bent or inclined equally toward each other until the edges of webs *b* thereof meet at a point about, say, twelve inches from the ends of the bolster, whereupon they 5 are again bent so that from said point of initial contact to the ends the plates *a* of said sections are parallel and the edges of the webs *b* thereof remain in contact. These end portions of said upper and lower sections are 10 secured together by vertical bolts *r* and *s*, which, preferably, are passed through suitable bolt-holes in plate *a* between the webs *b* and beads *c* thereof. These bolts *r* and *s* may be independent of the guide-blocks *V* V, 15 but I prefer to use them in conjunction therewith.

The guide-blocks *V* are constructed so as to provide the usual vertical guide-channel 5 in their outer surfaces, and on each side of 20 this channel they are provided with lugs 6, which are so formed that their flanged end edges bear against the outer vertical surfaces of the webs *b* and are provided with vertical knuckles 7, down through which bolts *r* and 25 *s* extend. The knuckle 8 next the end of the bolster has its center of length cut away, and between the divisions thereof I insert the adjacent lug 9 of the end plate 10. This end plate 10 is similar in function and construction to the end plate 1 of the body-bolster; but its fastening-lugs 9 extend inward from its side edges and lap against the outer surface of webs *b* between lugs 8 instead of against the inner surface of said webs.

35 The body of the guide-block *V* projects inward at a point about in transverse alignment with the center of width and height of the guide-channels 5 thereof and is so formed that its inner end is preferably rectangular 40 in cross-section and forms a key 12, which enters the rectangular opening 13, made by making corresponding recesses in the webs *b* of the upper and lower sections at such a point that when the edges of the webs of said sections are brought together said rectangular 45 opening 12 results.

The end plate 10 reinforces and strengthens the ends of the bolster in a transverse direction, and the keys 12 of the guide-block 50 prevent the longitudinal displacement or shearing strain of the two sections and remove a great deal of said shearing strain that would otherwise fall on the bolts *r* and *s*.

In order to complete the bolsters hereinbefore described, I secure to the under side of 55 the body-bolster by rivets or bolts extending through the lugs thereof and through the plate *a* of the under section at points preferably between the webs *b* and the longitudinal 60 sides thereof and the segmental side bearing *W*, and I secure to the upper surface of the truck-bolster in the same manner the side bearing *U*. In order to economize, I prefer to utilize the bolts *r* used in the truck-bolster to 65 secure the upper and lower sections together and also to fasten one end of the guide-block

thereto in securing the said side bearing *U* to the truck - bolster. This is easier accomplished by making the basal lugs on one side of said side bearing *U* of such dimensions 70 that said bolts *r* can be passed through the bolt-opening therein.

While I much desire the use of the beads *c* in the rolled-steel beams from which the upper and lower sections of the bolster are 75 made, yet it is obvious that said beads might be dispensed with. These beads serve to greatly strengthen the beams to resist the side or transverse pressure thereon and are particularly used in the beams used in construction of the body-bolster.

I do not wish to be confined to the exact means hereinbefore described and shown to fasten the ends of the upper and lower sections of my improved bolsters together. 85 Skilled workmanship would suggest a great many other means and devices for accomplishing this purpose, especially when the peculiar means employed by me in the construction of said bolsters are disclosed.

What I claim as new is—

1. In a bolster for cars, a metallic beam consisting of a flat plate provided with a plurality of parallel longitudinal webs projecting from the face of the plate between its 95 edges.

2. In a bolster for cars a rolled-metal beam consisting of a flat plate provided with parallel longitudinal webs and longitudinal beads next the side edges thereof.

3. In a bolster for cars a rolled-metal beam consisting of a flat plate provided with parallel longitudinal webs projecting at right angles therefrom between its center of width and its longitudinal side edges, and provided 105 with longitudinal beads next said side edges.

4. A bolster for cars comprising a pair of beams, each provided with a longitudinal web located between its edges, said webs extending toward each other, and means for 110 uniting said beams.

5. A bolster comprising a pair of beams, each provided with one or more vertical, longitudinal webs located between its edges, said webs extending toward each other, and 115 being separated at their central portions and brought into contact and union at their ends.

6. A bolster for cars consisting of upper and lower sections of rolled - metal beams each comprising a flat horizontal plate having longitudinal webs, and vertical plates which have their longitudinal side edges flanged and are secured to the webs of and hold the central portions of said sections a suitable distance apart; said sections being 120 so arranged one above the other that the webs of one section project toward and aline with those of the other, and said sections having their end portions bent toward the other so that the webs thereof come in contact and are 125 suitably fastened together.

7. A bolster for cars consisting of upper

and lower sections of rolled-metal beams, each comprising a flat horizontal plate having longitudinal webs, and vertical plates having their longitudinal side edges flanged 5 and secured to and holding the central portions of said sections a suitable distance apart; said sections being so arranged, one above the other, that the webs of one section project toward the others, and said sections 10 having their end portions bent toward the other so that the webs thereof come in contact and are suitably fastened together.

8. A bolster for cars consisting of upper and lower sections of rolled-metal beams each 15 comprising a flat horizontal plate having longitudinal webs, and vertical plates having their longitudinal side edges correspondingly flanged and having longitudinal ridges projecting from the other side thereof; said vertical plates being secured to the web of said sections so that the edges of said webs are seated against the sides of said ridges so as to hold the central portions of said sections a suitable distance apart; said sections being 20 so arranged, one above the other, that the webs of the one section project toward and are coterminous with those of the other, and said sections having their end portions bent toward the other so that the webs thereof 25 come in contact and are suitably fastened together.

9. A car-bolster comprising two sections, each consisting of a plate and an inwardly-extending web, means for centrally separating 30 said sections having surfaces engaging the inner edges of the webs to form bearings therefor, and means for uniting the ends of the sections.

10. A bolster for cars consisting of upper 40 and lower sections of rolled-metal beams each comprising a flat horizontal plate having longitudinal webs, and so arranged, one above the other, that the webs of one section project toward and are coterminous with the other, vertical plates secured to the inner 45 sides of the webs, and holding the central portions of said sections a suitable distance apart, transverse bolts securing said plates to said webs and sleeves placed between said vertical plates through which said bolts pass; said sections having their end portions bent toward the other so that the webs thereof come in contact and are suitably fastened together.

55 11. A bolster for cars consisting of centrally-separated upper and lower sections of rolled-metal beams comprising a horizontal plate having longitudinal webs, said sections being so arranged that the webs of one project toward those of the other, the end portions of said sections being inclined or bent toward each other until the webs thereof come in contact and then bent parallel to each other the remainder of their length and fastened together, in combination with an end plate 60 placed flat against the ends of said united sec-

tions so that their flanged edges conform to the outer contours of and embrace the same.

12. A bolster for cars consisting of upper and lower centrally-separated sections of 70 beams comprising a horizontal plate having longitudinal webs; said sections being so arranged that the webs of one project toward those of the other, and, having their end portions bent toward the other until their 75 webs come in contact and then being parallel the remainder of their lengths, in combination with a suitable casting fitting between the plates of the parallel end portions of said sections, end plates conforming to the outer 80 contours of the ends of said united sections and having its ends flanged so as to embrace the same and having inwardly-projecting lugs, and vertical bolts passing through the plates of said sections, through said castings 85 and the lugs of said end plates.

13. A bolster for cars consisting of upper and lower centrally-separated sections of beams comprising a horizontal plate having parallel longitudinal webs, respectively projecting therefrom between its center of width and its side edges, and having longitudinal marginal beads next said side edges; said sections being so arranged that the webs of one project toward and are in the same vertical 95 plane as those of the other, and, one or both, having their end portions bent toward the other until said webs come in contact and are secured together.

14. A car-bolster consisting of an upper and 100 a lower section, each comprising a flat plate having a longitudinal web, said webs being arranged in opposition to each other and brought into contact near their ends, a key 105 passing through an opening in said webs, means for securing one end of said key to the opposing plates on one side of the web, and means for holding the other end of said key in engagement with the webs on the other side thereof.

110 15. A car-bolster consisting of an upper and a lower section, provided with opposing webs, said webs being brought into contact near their ends, a key passing through an opening in said webs, and means for securing said 115 key to the two sections on both sides of the webs.

16. A car-bolster consisting of an upper and a lower section each provided with two webs, arranged to oppose those on the other section, 120 the opposing webs being brought into engagement near their ends and provided with registering apertures, a key passing through said apertures having exterior and interior knuckles, means for securing the exterior knuckles 125 to the two sections, and an end plate having lugs to engage the interior knuckles.
